UNITED STATES PATENT OFFICE.

FREDERICK M. FUREY, OF LONG BEACH, CALIFORNIA.

GRATING.

Application filed December 11, 1924. Serial No. 755,161.

This invention relates to grating such as is used for basement covers, manhole covers, fire escapes, stair case treads, etc.

It is an object of this invention to provide a grating of this character which will be superior to other gratings, inasmuch as it will possess great strength. The grating of my invention is especially designed to have a minimum of flexure, either in a transverse or a longitudinal direction. I accomplish this object by providing a grating having transverse members and longitudinal members which cross one another and are secured together.

It is a further object of my invention to provide a grating of the character mentioned having a novel joint for securing the transverse and longitudinal members together, this joint being extremely durable. The transverse members of a grating of my invention are wave-shaped and are arranged so that alternate points or crests of adjacent transverse members engage. At the point of engagement I provide slots and openings

in a manner to form bridges. The longitudinal members are provided with openings defining longitudinal bridges above said openings and securing lugs situated adjacent to and below said openings. The longitudinal and the transverse members are assembled in such a manner that the bridge portions of the transverse members extend through the openings in the longitudinal members and so that the lug portions serve to securely retain the bridges in the openings.

It is a further object of my invention to provide a grating of the character mentioned which may be produced at a small cost. I accomplish this object by providing grating of such a design that it may be readily made by a few simple operations.

Other objects and advantages of the invention will appear in the following description.

Referring to the drawing in which I show a preferred form of my invention solely for illustrative purposes,

Fig. 1 is a fragmentary perspective view of a grating embodying the features of my invention.

Fig. 2 is a section taken on a line 2—2 of Fig. 1.

Fig. 3 is a section taken on a line 3—3 of Fig. 1.

Fig. 4 is an enlarged fragmentary per-

spective detail of certain members of the grating shown in Fig. 1, these members being disposed in a position previous to the assembling thereof.

Fig. 5 is a fragmentary view showing the members in Fig. 4 in assembled position, but previous to the locking together thereof.

Fig. 6 is a view similar to Fig. 5, but showing members locked together.

With particular reference to Fig. 1 of the drawing, the form of my invention shown comprises transverse members 11 and longitudinal members 12. The transverse members 11 are wave-shaped as shown, and are arranged so that alternate points or crests 13 of adjacent transverse members contact, thus forming diamond-shaped openings. At the points 13 of the wave-shaped transverse members 11 slots 15 are provided, these slots being cut from the top edge of the members 11 in such a manner as to provide lower transverse bridge portions 16, the slots of the adjacent transverse members aligning as clearly shown in Fig. 4 of the drawings.

The longitudinal members 12 are provided with openings 18 defining upper longitudinal bridge portions 16^a and the web portions 19 below the openings 18 are sheared at 20 so as to provide securing lugs 21. When the members 11 and 12 are assembled as shown in Figs. 1, 2, 3, 5 and 6 of the drawings, lower transverse bridge portions 16 rest in the openings 18, these bridge portions 16 being retained in the openings 18 by means of lugs 21 engaging beneath said bridge portions. A rim member 23 is extended around the grating, the ends of the transverse and longitudinal members 11 and 12 being secured thereto as by welding as indicated at 24 in Fig. 1.

In constructing the grating of my invention the lugs 21 are bent as indicated in Fig. 4, these lugs being bent substantially on dotted lines 26 of Fig. 3, so as to provide a receiving throat 18^a affording access to the openings 18.

After the transverse members 11 are positioned as shown in Fig. 1 they are assembled with the longitudinal members 12 substantially as shown in Fig. 5 of the drawings. After the members are assembled as shown in this figure, the lugs 21 are again bent into securing position beneath the bridge portion 16 as shown in Fig. 6, thus retaining the bridge portions 16 of the transverse members 11 in the openings 18 of the

longitudinal members 12 with the side walls of the slots 15 embracing the upper longitudinal bridge portions of said longitudinal members. Experience has proven that the 5 lug members are sufficiently strong to endure any stresses applied on either of the members tending to separate them. However, if desired, the lug members after they are bent into securing position may be welded.

10 I am able to provide an extremely strong grating due to the fact that the longitudinal and the transverse members cross one another and are rigidly secured together. The securing of each of these members with one 15 another provides a grating which presents a maximum resistance to flexure, either in a transverse or a longitudinal direction.

The construction of the grating is simple and the mechanical work necessary is very 20 small; therefore, the grating may be produced at a fairly low cost. It is obvious that the shaping of the parts and the assembling and securing of these parts require but small labor.

25 I claim as my invention:

1. In a grating of the class described, the combination of: longitudinal members having relatively spaced transverse openings each defining an upper longitudinal bridge 30 portion and a lower web portion split to form locking lugs; and wave-shaped transverse members slotted from their upper edges downwardly at the crests of each alternate bend and to a depth to leave adjacent lower 35 transverse bridge portions, the members being assembled so that the lower bridge portions of the transverse members extend through said openings in the longitudinal

members with the side walls of said slots embracing the upper longitudinal bridge 40 portions of the longitudinal members, and with the locking lugs engaging beneath and locking the transverse members within said openings.

2. In a grating of the class described, the 45 combination of: longitudinal members having openings which connect with slits which extend through the edges of said members; and transverse members slotted in one edge thereof and adapted to be received in said 50 openings through receiving throats formed by bending aside the material adjacent the slits, said transverse members being retained in said openings by said material when same is rebent to normal position and beneath the 55 unslotted edge of said transverse members.

3. In a grating of the class described, the combination of: a longitudinal member having an opening formed therein; cooperating lugs formed adjacent to said opening, said 60 lugs being adapted to be positioned to form a receiving throat connecting said opening with an edge of said longitudinal member; and a transverse member slotted in one edge 65 thereof and adapted to be extended into said opening through the throat connecting said opening and said edge, said lugs being movable into a position to close said opening and to engage beneath the unslotted edge of the 70 transverse member to secure said transverse member in said opening.

In testimony whereof, I have hereunto set my hand at Los Angeles, California, this 6th day of December, 1924.

FREDERICK M. FUREY.
